Term of patent 14 years

(Cl. D52—2)

fig. 1

The undisclosed side of the dispensing container is substantially the same in appearance as the side shown with the exception of the lever.

I claim:

The ornamental design for a dispensing container for tablets, capsules and the like, as shown and described.
